DESIGN FOR A DOLL STROLLER

Myer Cohen, Beverly, Mass.

Application January 31, 1945, Serial No. 117,688

Term of patent 14 years

(Cl. D34—15)

To all whom it may concern:

Be it known that I, Myer Cohen, a citizen of the United States, residing at Beverly, in the county of Essex and Commonwealth of Massachusetts, have invented a new, original, and ornamental Design for a Doll Stroller, of which the following is a specification, reference being had to the accompanying drawing forming a part thereof.

In the drawing, the figure is a perspective view of a doll stroller showing my new design.

I claim:

The ornamental design for a doll stroller, as shown.

MYER COHEN.
